UNITED STATES PATENT OFFICE.

HIRAM W. WHITE, OF YANKTON, DAKOTA TERRITORY.

METALLIC CURBING-SECTION.

SPECIFICATION forming part of Letters Patent No. 408,057, dated July 30, 1889.

Application filed May 20, 1889. Serial No. 311,381. (No model.)

To all whom it may concern:

Be it known that I, HIRAM W. WHITE, a citizen of the United States, and a resident of Yankton, in the county of Yankton and Territory of Dakota, have invented certain new and useful Improvements in Metallic Curbings-Sections; and I do declare the following to be a full, clear, and exact description of the invention, such as will enable others skilled in the art to which it appertains to make and use the same, reference being had to the accompanying drawings, and to letters of reference marked thereon, which form a part of this specification.

15 Figure 1 of the drawings is a perspective view of the curbing. Fig. 2 is a horizontal section; and Figs. 3, 4, and 5 are detail views.

This invention has relation to metallic sectional curbing for pavements, steps, flower-beds, &c.; and it consists in the novel construction and combination of parts, as hereinafter set forth.

20 In the accompanying drawings, the letters A A designate the curb-sections, and B B' the holders and anchors.

B' indicates an oblique anchor for a corner of the curbing.

The curb-sections are preferably cast with a bead or molding C along their upper marginal portions, and this upper portion is extended a little beyond the lower portion of the section, which is rabbeted to provide an acute-angled shoulder D to engage a reversely-beveled shoulder on the anchor.

35 The anchor or holder consists of a horizontally-extended plate or key E, the lower margin of which is designed, when the parts are set up in position, to be on a level with the lower edges of the curbing-sections, while the 40 upper edge F is depressed or lower than that of the upper edge of said curbing-sections. The inner end of the anchor is provided with a transverse enlargement or foot G, and the outer end with a head or post H, laterally enlarged and extending upward to receive the 45 bead or molding of the sections. The key portion E is extended upward along the rear surface of the head H to within a short distance of its top, and is reversely beveled at 50 its upper end to form a notch-shoulder K,

adapted to receive the shoulders at the ends of the curb-sections when the latter are placed in position on each side of the key-portion E against the rear surface of the head, which stands in front of the sections at the joint and holds them to position.

The molding or bead C projects outward beyond the head sufficiently to protect it from engagement with the wheels of vehicles striking the curb. The rabbet at the ends of each 60 section is designed to measure just half the thickness of the key portion of the anchor, so that when the curbing-sections are put together their upper marginal portions will abut against each other.

65 In setting this curbing the anchors are placed in position on the bed-surface, and the curbing-sections are engaged therewith and are held up by said anchors until the brick, gravel, or other material of the wall or bed is 70 filled in behind the curbing and on each side of and upon the anchor-keys.

The corner-anchor B' is constructed somewhat larger than the anchors which hold the main sections, and the lateral enlargements or 75 flanges of its post portion or head have their rear or enlargement surfaces in angular relation to each other, so that the sections of curbing forming the corner will be held in proper angular position. Said corner-anchor also has 80 its post portion extended upward at the top to form a sector-shaped abutment L, against the sides of which the ends of the upper or beaded portions of the curb-sections forming the corner abut.

85 Having described this invention, what I claim, and desire to secure by Letters Patent, is—

1. The metallic curbing-anchor having a head or post portion adapted to engage the 90 joining curbing-sections and having the extended lower or key portion in rear of said head or post portion, substantially as specified.

2. The metallic curbing-anchor consisting of the laterally-enlarged head or post having 95 the reversely-beveled shoulder in rear below its upper edge, and the rearwardly-extending key portion extending from its lower portion and terminating in an enlargement or foot at its inner end, substantially as specified.

3. The combination, with metallic curbing-sections rabbeted at their ends and having acute-angled shoulders, of the anchors, their reversely-beveled shoulders, and rearwardly-extending key portion, substantially as specified.

4. The combination, with metallic curbing-sections, of the anchor-posts having rearwardly-extending key portions and adapted to

engage and hold said curbing-sections in position, substantially as specified.

In testimony whereof I affix my signature in presence of two witnesses.

HIRAM W. WHITE.
